UNITED STATES PATENT OFFICE.

KARL SCHMIDT, OF HERMSDORF, NEAR BERLIN, GERMANY, ASSIGNOR TO GENERAL ELECTRIC COMPANY, A CORPORATION OF NEW YORK.

TRANSFORMER CONNECTION.

1,072,042.

Specification of Letters Patent.

Patented Sept. 2, 1913.

Application filed August 25, 1911. Serial No. 646,007.

To all whom it may concern:

Be it known that I, KARL SCHMIDT, a subject of the Emperor of Germany, residing at Hermsdorf, near Berlin, Germany, have 5 invented certain new and useful Improvements in Transformer Connections, of which the following is a specification.

My invention relates to the gradual regulation of an alternating voltage by means of 10 a transformer and a regulator, and has for its objects the provision of a method of operation and means for carrying out the method whereby the entire transformer may be at all times in service and where the number 15 of leads from the transformer is small.

It is common to regulate an alternating voltage by employing a transformer having at least one winding divided into groups of turns; and an induction potential regulator. 20 The passage from one step to the next, that is the changing of the voltage as one side of the line is changed from one group to the next, is made gradually by the aid of a regulator; generally the groups are composed 25 of approximately the same number of turns since the regulator is required to furnish a voltage at least equal to that of the largest group. In the devices in use prior to my invention, those groups which at any particular time were not in effective use, that is not carrying load, when left connected to the rest of the transformer, had induced in them a voltage higher than that on the line; this 30 at times reached a dangerous value; to prevent accidents it has been common to provide special means to disconnect from the rest those groups which are not in active use. In these devices there are a large number of leads.

Broadly my invention consists in the provision of a method of operation whereby all the groups of the transformer winding are at all times in active operation and are subject to no voltage above that of the line and 45 where the regulation is accomplished by the regulator and by reversing relatively to the rest of the winding, certain groups which with the regulator produce at times a zero effect, and in the provision of an apparatus 50 for carrying out this method.

With my invention the groups may contain any number of turns, but I prefer to use groups having different numbers of turns in order to reduce the number of leads; this 55 may be done very advantageously and pref-

erably by using groups, the numbers of turns of which form a geometrical series.

My invention is not limited to the division of one winding only of a transformer into groups; where, however, but one winding is divided into groups that winding may be either the primary or secondary. In any case in maximum voltage and load the regulator needs only to equal the smallest transformer group with which it is coöperating. 60

The single figure in the drawing, which forms a part of this specification, shows diagrammatically a transformer, one winding of which is formed in three groups of turns, and a potential regulator in connection 70 therewith.

It will, of course, be understood that the transformer is not necessarily limited to having three groups of turns, but that any number of groups may be used so long as there 75 is a plurality. Also, it is not necessary that all the groups have a common core and be supplied by a single line.

The transformer illustrated has one winding divided into three groups w , $2w$, $4w$, the 80 group $2w$ having twice as many turns as the group w and the group $4w$ having four times as many turns. In addition to the transformer a potential regulator r is used. Any regulator which may be adjusted from maximum in one direction through zero to maximum in the opposite direction may be used. I have shown diagrammatically a 85 common induction potential regulator having one winding and parallel with one winding of the transformer, and the other winding adapted to be connected in various ways with that other winding of the transformer which is divided into groups. This connection of the inducing winding of the induction regulator is suitable when the undivided winding of the transformer is the primary thereof; other connections of the inducing winding of the regulator may be more desirable at times, as for example when 90 the undivided winding is the secondary. 95

The wires 1 and 2 convey current to or from the divided winding according to whether this winding is the primary or the secondary of the transformer. One of these 105 wires 2 is attached direct to the group $4w$. To the other side of this group is attached the lead 3, to which lead the three switches 4, 5 and 6 are connected. These switches at various times connect the lead 3 to the con- 110

necting leads 7, 8 and 9. To the group $2w$ are connected the leads 10 and 11; one side of this group may be connected through the lead 10 and the switch 12 to the connecting lead 14, or through this lead and the switch 13, to the connecting lead 8 and the group w ; the lead 11 is permanently attached to the connecting lead 7. One side of the group w is permanently connected to one side of the regulator r , the other sides of the two respectively being permanently connected to the connecting lead 8 and to the connecting leads 9 and 14. The connecting leads 7, 8 and 9 may at various times be connected to the wire 1 through the switches 15, 16, 17.

The winding of the transformer which I have shown as divided into groups may be regarded as the secondary winding supplying current to the wires 1 and 2. To raise the voltage on these wires from zero to maximum the operation may be as follows: The switches 4, 13 and 17 are closed and the regulator is so set that it aids the group w . The circuit from wire 2 is downward through the group $4w$, along the lead 3 to the switch 4, through the connecting lead 7 to the lead 11, and thence upward through the group $2w$, down through the lead 10 to the switch 13, from thence upward through the winding w and from there through the potential regulator and the switch 17 to the wire 1. We have assumed that the regulator is adjusted to give its maximum voltage in such a direction at any particular instance as to aid the group w . Hence we have the group $4w$ opposed by the regulator and the groups w and $2w$, the combined effect of the last three equaling the effect of the group $4w$ with the result of no current on the wires 1 and 2. Suppose now that the regulator be so adjusted that it is neutral: the circuit remains the same, but now the regulator r is neither aiding nor opposing any group of windings and the group $4w$ is now opposed by the groups $2w$ and w only; there is an effect on the wires 1 and 2 of a group having a number of turns equal to the difference between the number of turns on the group $4w$ and the sum of the turns of the groups $2w$ and w , or w . Now adjust the regulator so that it opposes the group w ; the circuit is still the same, but now we have the group $4w$ aided by the regulator, which is the equivalent of a group having the same number of turns as the group w , and opposed by the groups $2w$ and w , resulting in an effect on the wires 1 and 2 of a single group having twice the number of turns as the group w . At this stage the switches 12 and 16 may be closed, short circuiting the group w and the regulator r ; since these two equal and oppose each other, there is no change in effect on the wires 1 and 2. The switches 13 and 17

may now be opened. By tracing the new circuit, it will be seen that we have the groups $4w$ and w opposed by the group $2w$ and the regulator with the same effect on the wires 1 and 2 as before the changing of the switches. The regulator may now be changed to zero and to maximum in the opposite direction, the effect on the wires 1 and 2 passing gradually from the effect of $2w$ turns through $3w$ turns to $4w$ turns. After reaching this stage the switches 5 and 15 may be closed, short circuiting groups $2w$ and w and the regulator, the sum of the effects of which is equal to zero, and the switches 4 and 16 opened. By operation of the regulator the effect now passes from $4w$ to $5w$ and to $6w$. The switches 13 and 6 may now be closed and 5 and 12 opened, after which the regulator may again be operated and the effect changed from $6w$ to $7w$ and to $8w$, the maximum for the apparatus, all the groups and the regulator assisting.

The operation of the switches and regulator to obtain the various voltages may be easier understood from the following, the signs representing the various coils and the regulator, at any particular instant, as assisting or opposing the group $4w$ and the sums showing the results on the wires 1 and 2 in effective turns:

Switches 4, 13 and 17 closed:

$$\begin{aligned} 4w - 2w - w - r &= 0 \\ 4w - 2w - w + 0 &= w \\ 4w - 2w - w + r &= 2w. \end{aligned}$$

100

Switches 4, 12 and 16 closed:

$$\begin{aligned} 4w - 2w + w - r &= 2w \\ 4w - 2w + w + 0 &= 3w \\ 4w - 2w + w + r &= 4w. \end{aligned}$$

105

Switches 5, 15 and 12 closed:

$$\begin{aligned} 4w + 2w - w - r &= 4w \\ 4w + 2w - w + 0 &= 5w \\ 4w + 2w - w + r &= 6w. \end{aligned}$$

110

Switches 6, 13 and 15 closed:

$$\begin{aligned} 4w + 2w + w - r &= 6w \\ 4w + 2w + w + 0 &= 7w \\ 4w + 2w + w + r &= 8w. \end{aligned}$$

It will, of course, be apparent that it is not necessary that the regulator be brought to maximum or to zero, but that it may be held at rest in any mid position should a desired voltage necessitate it.

My invention is not limited to the specific connections and switches I have shown, but I regard it as broad enough to include any set of connections and switches which will allow substantially the operation I have disclosed above, namely, the reversal of the group or groups and the regulator whose combined effect may equal zero, relatively to the other groups of the transformer winding.

What I claim as new and desire to secure by Letters Patent of the United States, is,—

130

1. In combination, groups of transformer windings, the numbers of turns of the various groups forming approximately a geometrical series, a potential regulator, and means for reversing the relation of the smallest group and the regulator to the other groups.
2. In combination, groups of transformer windings, the numbers of turns of the various groups forming approximately a geometrical series, a potential regulator, and means for short circuiting the smallest group and the regulator and for reversing their relation to the other groups.
3. In combination, two groups of transformer windings having different numbers of turns, a potential regulator, and means for reversing the relation of one group and the regulator to the other group.
4. In combination, groups of transformer windings, the numbers of turns of the various groups forming approximately a geometrical series, a potential regulator, and means for reversing the relation of the smallest group and the regulator to the other groups and for reversing another group.
5. In combination, groups of transformer windings, the numbers of turns of the various groups forming approximately a geometrical series, a potential regulator, and means for short circuiting certain of the groups and the regulator and for reversing their relation to the other groups.
6. In combination, a transformer winding, a potential regulator, and means for reversing the regulator and a part of the winding relative to the rest of the winding.
7. In combination, a transformer winding, a potential regulator, and means for short circuiting the regulator and a part of the winding and reversing their relation to the rest of the winding.
8. The method of gradually regulating or varying an alternating voltage by a potential regulator, and a transformer winding connected in series, which consists in changing the voltage by means of the regulator until the effect produced by the regulator and a part of the windings equals zero, then reversing this part of the winding and the regulator relatively to the rest of the winding, and again changing the voltage by means of the regulator.
9. The method of gradually regulating or varying an alternating voltage without opening the circuit by a potential regulator, and a transformer winding connected in series, which consists in changing the voltage by means of the regulator until the effect produced by the regulator and a part of the winding equals zero, then short circuiting this part of the winding and the regulator, reversing them relatively to the rest of the winding and the line, and opening the first connections of the first mentioned part of the windings and the regulator to the rest of the winding and the line, and again changing the voltage by means of the regulator.

In witness whereof, I have hereunto set my hand this 22 day of July, 1911.

KARL SCHMIDT.
